UNITED STATES PATENT OFFICE.

JAMES K. TUFTS, OF BOSTON, MASSACHUSETTS.

TOOL-HOLDER.

1,306,039.

Specification of Letters Patent. Patented June 10, 1919.

Application filed May 31, 1917. Serial No. 171,810.

To all whom it may concern:

Be it known that I, JAMES K. TUFTS, a subject of King George V of England, residing at Boston, in the county of Suffolk 5 and State of Massachusetts, have invented new and useful Improvements in Tool-Holders, of which the following is a specification.

This invention relates to an improved tool 10 holder to be used in connection with the tool post of a lathe, planer or shaper. The cutting tools of metal are made of very expensive steel and it is the object of this invention to provide a holder for such tools 15 which will firmly clamp a small piece of steel, formed as a cutter, to a holder such as is practicable in form and size to be used in connection with the tool post of a lathe, planer or shaper.

It is further the object of this invention 20 to provide a device of the character set forth in which the tool is clamped to the holder in such a manner as not to injure the same by cracking it or by causing it to be crystallized 25 at certain portions thereof so that it will break when pressure is applied thereto.

The invention consists in a tool holder 30 having a recess therein adapted to receive a tool and certain specific means for firmly 35 clamping either a short or long tool to said holder, as set forth in the following specification and particularly pointed out in the claims.

The invention further consists of a device 40 of the character set forth in which the holder is so mounted that it can be rotated so as to place the tool holder thereof at different angles according to the nature of the work being performed.

The invention still further consists in the 45 combination and arrangement of parts set forth in the following specification and particularly pointed out in the claims thereof.

In the accompanying drawings I have 50 illustrated several forms embodying my invention, all of said forms, however, containing the same fundamental principles and illustrating the different ways in which my invention may be used to suit varying classes of work.

Referring to the drawings:

Figure 1 is a side elevation of one embodiment of my invention, the same being particularly adapted to be used in connection 55 with the tool post of a lathe.

Fig. 2 is a plan view of the same.

Fig. 3 is a side elevation of another embodiment of my invention, also adapted to be used in connection with the tool post of a lathe. 60

Fig. 4 is a plan view of that form of my invention illustrated in Fig. 3.

Fig. 5 is a side elevation of another embodiment of my invention which is adapted to be used particularly in connection with 65 the tool post of a planer or shaper.

Fig. 6 is a plan view of the form of my invention illustrated in Fig. 5.

Fig. 7 is a side elevation of another embodiment of my invention illustrating the 70 tool holder rotatably mounted upon a supporter which is adapted to be used in connection with the tool post of a planer or shaper.

Fig. 8 is a plan view of the form of my 75 invention illustrated in Fig. 7.

Like numerals refer to like parts throughout the several views of the drawings.

In the drawings, referring to Figs. 1 and 2, 10 is the holder, and 11 the tool which 80 projects into a hole 12 in which it forms a sliding fit. The hole 12 extends longitudinally through the holder at an angle thereto and is intersected by a slot 13 which extends at an acute angle to said hole 12 and 85 in which is located a clamping lever 14 pivoted to the holder 10 by means of a pivot 15. A screw 16 has screw-threaded engagement with the lever 14 and the inner end thereof projects into a recess 17 formed in 90 the bottom of the slot 13, the metal in the immediate vicinity of said recess being hardened.

It will be noted that the inner end of the screw 16 bears against a portion of the 95 holder 10 which projects between the bottom of the slot 13 and the top of the hole 12, so that whether the piece forming the tool 11 is long enough to extend entirely through the hole 12, or only a very short distance into 100 said hole, the screw 16 will bear against said portion of the holder 10, and will clamp the tool, whether long or short, into the hole 12 under exactly the same conditions.

It will be noted that the clamp lever 14 105 has one edge 18 thereof arranged to contact with the tool 11 on both sides of a plane A—A which extends transversely of the tool 11 and hole 12 and at right angles to the bottom of said hole and passes 110 through the median axial line of said pivot 15, so that said edge 18 bears along the

upper edge of the tool 11 from the front of the holder 10 to and beyond the plane A—A, and consequently it will be seen that when the screw 16 is operated to rock the clamp 5 lever 14 upon its pivot 15, it will bear against the upper edge of the tool 11 for a substantial distance from the plane A—A and will have no tendency to nick or crystallize said tool to make it crack. Moreover, if the tool 11 is very short, the edge 18 of the lever 14 will have a firm hold and comparatively long bearing thereon.

It will be seen that as the lever 14 is operated, as hereinbefore set forth, to clamp 15 the tool in the holder, the portion of the edge 18 immediately adjacent to the plane A—A will act as a wedge between the pivot 15 and the tool 11 to firmly clamp said tool to the holder and that any force exerted 20 upon the tool 11 during its operation in cutting metal which tends to force said tool backwardly in the hole 12 will cause the clamping action of the lever 14 to be increased and the tool to be thus still more 25 firmly held and clamped within the holder 10.

The edge 19 of the lever 14, it will be seen, extends at an angle to the edge 18 of said lever and along adjacent to the bottom of the slot 13, so that there is opportunity for a substantial amount of metal of 30 the holder 10 to project between the bottom edge 19 of the lever 14 and the top edge of the hole 12, so that a substantial and strong base is provided against which the 35 screw 16 bears.

The operation of the tool is as follows: The holder 10 is inserted in the tool post of a lathe in the usual manner. The tool 11 is placed in the hole 12 and is clamped therein by means of the lever 14 and clamping screw 16. Turning said screw to advance the same causes the lever 14 to clamp the tool in the hole 12 and vice versa.

Now referring to Figs. 3 and 4, 20 is the 45 holder, 21 the tool, 22 the hole in which said tool is seated, 23 the slot for the clamping lever 24, which lever is pivoted at 25 and is tipped upon said pivot by a clamping screw 26, the lower end of which bears 50 against a recess 27 in the holder 20. The edge 28 bears against the tool 21 and the edge 29 of said lever stands at an angle to the edge 28 and at a slight distance from the bottom of the slot 23. In this embodiment 55 of my invention it will be seen that the edge 28, which contacts with the tool 21, extends on opposite sides of a plane B which stands at right angles to the edge of the tool 21 and contains the median axial line of the pivot 25.

In the form of my invention illustrated in Figs. 5 and 6, 30 is the holder, 31 the tool, 32 the hole in which said tool is seated, 33 the slot in which the lever 34 is located. 65 35 is the pivot of said lever 34, 36 the

clamping screw, 37 the recess into which the end of the clamping screw projects, 38 the edge of the lever which bears against the tool 31 and 39 the edge of said lever which extends at an angle to the edge 38 and 70 adjacent to the bottom of the slot 33.

It will be noted that the plane C which contains the median axial line of the pivot 35 intersects the contacting edge 38 of the lever 34 at a substantial distance from the 75 point where the tool projects from the front of the holder 30.

In Figs. 7 and 8 a modified form of my invention is embodied in which the tool holder is rotatable so that the tool may be 80 presented at different angles to the work. In this embodiment of my invention 40 is the holder, 41 the tool, 42 the hole in which said tool is seated, 43 the slot in which the clamp lever 44 is located, said 85 clamp lever being pivoted at 45 to the holder 40. 46 is the clamp screw which tips the holder upon its pivot in order that the edge 48 of said lever may bear against the edge of the tool 41 and clamp the same in the 90 holder. It will be noted that the edge 48 stands at an angle to the edge 49 of said lever.

The holder 40 has a shank 50 which is 95 rotatably mounted in a supporting member 51, the shank 52 of said supporting member projecting into the tool post of a planer or shaper in the usual manner. Said tool holder 40 is locked in position by means of a pin 53 which projects into any one of the recesses 54 provided in the upper edge of the boss 55 of the supporting member 51 and is clamped in position by means of a nut 56 having screw-threaded engagement with the shank 50.

The general operation of the different 100 embodiments of my invention is substantially the same, except that in the form of my invention illustrated in Figs. 7 and 8 the tool can be set at different angles to the 105 supporting member 51 while the supporting member remains in the tool post.

Having thus described my invention, what I claim and desire by Letters Patent 110 to secure is:

1. A tool holder having, in combination, a holding member having a recess therein adapted to receive a tool, said holding member also being provided with a slot intersecting said recess, a clamping lever located 115 in said slot pivoted to said holding member and arranged to bear against a tool located in said recess and a screw having screw-threaded engagement with said lever and adapted to bear against said holding member outside said recess.

2. A tool holder having, in combination, a holding member having a hole extending therethrough adapted to receive a tool, said holding member also being provided with 120

a slot intersecting said hole, a portion of said holding member projecting between said hole and slot and forming the bottom of said slot, a clamping lever located in said slot pivoted to said holding member and arranged to bear against a tool located in said slot and a screw having screw-threaded engagement with said lever and adapted to bear against said portion of said holding member which forms the bottom of said slot.

3. A tool holder having, in combination, a hole extending therethrough adapted to receive a tool, said holding member also being provided with a slot intersecting said hole, a portion of said holding member projecting between said hole and slot and forming the bottom of said slot, a clamping lever located in said slot pivoted to said holding member and arranged to bear against a tool located in said slot and a screw having screw-threaded engagement with said lever and adapted to bear against said portion of said holding member projecting between said hole and slot, said holding member having a recess therein into which the end of said screw is adapted to project.

4. A tool holder having, in combination, a holding member having a recess therein adapted to receive a tool, said holding member also being provided with a slot intersecting said recess, a clamping lever located in said slot, a pivot connecting said clamping lever to said holding member, one edge of said clamping lever adapted to contact with a tool located in said recess from the front end of said hole to the point in said hole nearest said pivot.

5. A tool holder having, in combination, a holding member having a recess therein adapted to receive a tool, said holding member also being provided with a slot intersecting said recess, a clamping lever located in said slot and pivoted to said holding member, said clamping lever having one edge thereof arranged to contact with said tool for a substantial distance and another edge thereof extending at an angle to said contacting edge and adjacent to the bottom of said slot and a screw having screw-threaded engagement with said lever and adapted to bear against the bottom of said slot.

6. A tool holder having, in combination,

a holding member having a recess therein 55 adapted to receive a tool, said holding member also being provided with a slot intersecting said recess, a clamping lever located in said slot and pivoted to said holding member, said clamping lever having one 60 edge thereof arranged to contact for a substantial distance with a tool located in said recess and another edge thereof extending at an angle to said contacting edge and adjacent to the bottom of said slot and a 65 screw having screw-threaded engagement with said lever projecting through said last-named edge and adapted to bear against a portion of said holding member located between said lever and said recess.

7. A tool holder having, in combination, a holding member having a recess therein adapted to receive a tool, said holding member also being provided with a slot intersecting said recess, a clamping lever located 75 in said slot, a pivot connecting said clamping lever to said holding member, said clamping lever having one edge thereof arranged to contact with a tool located in said recess for a substantial distance from the 80 front end of said recess toward a plane extending transversely of and at right angles to the bottom of said recess and containing the median axial line of said pivot and a screw having screw-threaded engagement 85 with said lever and adapted to bear against the bottom of said slot.

8. A tool holder having, in combination, a supporting member, a holding member rotatably mounted upon said supporting 90 member, means to lock said holding member to said supporting member, said holding member having a recess therein adapted to receive a tool and being also provided with a slot intersecting said recess, a clamping 95 lever located in said slot pivoted to said holding member and arranged to bear against said tool and a screw having screw-threaded engagement with said lever and adapted to bear against said holding member outside said recess.

In testimony whereof I have hereunto set my hand in presence of two subscribing witnesses.

JAMES K. TUFTS.
